UNITED STATES PATENT OFFICE.

CILIO B. YAW, OF ARLINGTON, NEW JERSEY, ASSIGNOR TO REMINGTON TYPEWRITER COMPANY, OF ILION, NEW YORK, A CORPORATION OF NEW YORK.

CABINET.

1,237,009.

Specification of Letters Patent. Patented Aug. 14, 1917.

Application filed September 20, 1916. Serial No. 121,277.

To all whom it may concern:

Be it known that I, CILIO B. YAW, citizen of the United States, and resident of Arlington, in the county of Hudson and State of New Jersey, have invented certain new and useful Improvements in Cabinets, of which the following is a specification.

My invention relates to cabinets and more particularly to typewriter cabinets.

10 The main objects of my invention, generally stated, are to provide a simple, strong, light and efficient cabinet of the character specified, which may be manufactured at small cost and so constructed as to provide 15 no place in the body of the cabinet where dust may accumulate.

To the above and other ends which will hereinafter appear my invention consists in the features of construction, arrangements 20 of parts, and combinations of devices set forth in the following description and particularly pointed out in the appended claims.

25 In the accompanying drawings, wherein like reference characters indicate corresponding parts in the different views,

Figure 1 is a front view of a cabinet constructed in accordance with my invention, the receptacles being shown swung into closed position in the cabinet.

30 Fig. 2 is a fragmentary top plan view of the same with the receptacles shown swung out of the cabinet to the open position.

Fig. 3 is a horizontal sectional view of 35 the cabinet.

Fig. 4 is a fragmentary detail front view partly in section showing one of the hinges by which the receptacles are hinged to the cabinet and certain of the details of construction.

40 Fig. 5 is a fragmentary vertical transverse sectional view of the cabinet showing one of the receptacles in its closed position.

Fig. 6 is a detail perspective view of the 45 metallic frame of the cabinet.

Fig. 7 is a fragmentary detail perspective view showing a portion of one of the rectangular frames of the receptacles with a catch carried thereby and by which the re-

50 ceptacle may be locked in its closed position.

The so-called sanitary cabinet of my present invention is intended primarily as a typewriter cabinet, and to this end is preferably of the table top variety and of a height

55 requisite to properly support a typewriting

machine on top thereof so that an operator seated at the cabinet may operate the machine. It should be understood, however, that the cabinet is available for other purposes, and its use is not limited to that specified.

The main frame of the cabinet shown in Fig. 6 is preferably made of sheet metal, the separate parts being united by screws or rivets to form a substantially rectangular frame which carries all parts such as the top and side panels and the receptacles which are hinged to the frame. The main frame comprises tubular posts or legs 1, angular in cross-section and united at the top thereof by angle-irons 2. These latter are connected together near their meeting ends by triangular plates 3 riveted at 4 to the angle-irons. The corner posts 1 are united at each end or side of the frame by sheet metal struts or diagonal braces 5 that are bolted to the end angle-irons at 6 and extend to the corner post where they are screwed thereto at 7. From thence the struts extend to tubular cross bars 8 where they are screwed thereto at 9. Each cross bar 8 is angular in cross-section and extends from the lower end of and forward to a rear corner post at one end or side of the frame, and is secured to said posts 1, as indicated at 10. Diagonally disposed cross rods 11 are connected together, at 12, where they cross and are connected at their ends, as at 12^a, to the upper and lower ends of the rear corner posts. A rear tubular cross bar 13 which is angular in cross-section and which extends lengthwise of the frame at the rear thereof is connected at its ends, as at 14, to the lower ends of the rear corner posts.

Sheet metal diagonally disposed angle-irons, braces or struts 15 extend from the end cross bars 8 (to which they are connected by the screws 9) to the rear cross bar 13 to which they are connected at 16. A caster or roller 17 is carried by each leg or corner post 1.

The sanitary frame thus produced is light and rigid, forming a substantial frame for the parts carried and supported thereby.

Each front corner post 1 carries a hinge member 18, each of which is in the nature of an angle-bracket secured by screws 19 to its post 1, and perforated at 20 to receive a headed pivot pin 21 suitably secured to the companion hinged members 22. Each

hinged member 22 is riveted or otherwise secured at 23 to a rectangular frame 24 of a hinged receptacle, designated as a whole by the reference numeral 25, which will be 5 hereinafter described in detail.

The upper side of each angle-iron 2 is perforated at 26 (see Fig. 6) for the reception of screws 27 which pass through said openings from beneath and take into a top panel 10 28. This panel constitutes an uninclosed top of the cabinet and may be of any suitable material; the panel being made of wood in the present instance. The screws 27 passing into the body of the panel 28 15 secure it to the top of the frame. In the present instance I have provided four cup-like metal members 29, each centrally apertured to receive a wood screw 30 by which each member is secured to the top of the cabinet. These members 29 are intended to 20 receive the rubber feet of a typewriting machine and prevent an accidental displacement of the machine on the top of the cabinet.

25 Each side or end of the cabinet is closed by a panel 31 of suitable material, wooden panels being employed in the present instance. Each panel 31 is secured at the bottom thereof to the associate cross bar 8 by 30 screws 32 (see Fig. 3). The upper end of each panel 31 is secured to a wooden cleat 33 (see Fig. 4) by screws 34. Each cleat is received in the adjacent angle-iron 2 of the frame. Angle-irons or strips 35 are secured 35 by screws 36 to the top panel and each angle-iron bears at one side against the associated side panel and prevents an inward movement of the upper end thereof.

From the foregoing description it will be 40 understood that the body portion of the cabinet is closed at top and both sides, but is open at the front, back and bottom and that no places are presented within the body of the cabinet for the accumulation of dust.

45 Each of the hinged receptacles, of which there are two in the present instance, is constructed as follows: Each receptacle embodies in its construction two rectangular frames 24 hereinbefore referred to. Each 50 side of the frame 24 is formed as an angle-iron from a continuous strip joined at its ends 37 (Fig. 3) by the hinged member 22 which is riveted thereto at both sides of the joint 37. One of these frames 24 is provided 55 at the top and one at the bottom of each receptacle, and the two frames are united by the side panels 38 of suitable material, wooden panels being employed in the present instance. These panels inclose their 60 receptacle on three sides, leaving the fourth or only remaining side open to give access to the receptacle. A similar top panel 39 and a bottom panel 40 are provided for each receptacle. The panels are secured to the 65 frames and are connected together by screws

41 which, as shown in Fig. 5, extend through openings in the frames 24 and into the side and top and bottom panels. Wooden cleats 42 are secured by screws 42^a to the side panels of each receptacle, in order to provide supports for shelves 43, which divide each receptacle into several compartments. 70

The front side of each rectangular frame 24 is apertured to receive a spindle 44, as shown in Fig. 7. The outer end of the 75 spindle is provided with a knurled head or finger piece 45, whereas the inner end thereof is connected to a catch or latch 46 adapted to be projected through an opening 47 in the frame 24. This latch is adapted to be 80 received behind the depending flange of the front angle-iron 2 of the main frame and thus lock the receptacle which carries said latch in its closed position.

From an inspection of Figs. 2 and 3 it 85 will be seen that each of the receptacles 25 is rectangular in cross-section forming a box-like structure pivoted at one corner on a vertical axis to a side of the cabinet at the front thereof so that each receptacle may 90 swing more than 90° on its hinges forwardly and outwardly from the closed position within the cabinet to an outermost position represented in Fig. 2. When the receptacles are 95 in the open position represented in Fig. 2, the open side of each of them is presented to the operator sitting at the front of the typewriter cabinet, so that stationery and other supplies contained within the receptacles are readily accessible to the operator 100 when the cabinet is in use. The top of each receptacle at this time provides a table-like surface available for use by the operator. It will also be understood more particularly from an inspection of Fig. 3 that when the 105 receptacles are swung into the cabinet the open side of each of them is brought adjacent to a side panel of the cabinet, thus closing each receptacle when it is swung into position in the cabinet. 110

What I claim as new and desire to secure by Letters Patent, is:

1. A typewriter cabinet, comprising a skeleton open front metallic frame composed of four legs, an open rectangular top frame supported by said legs, horizontal cross bars connecting the lower portions of said legs only at the sides and at the rear, upright diagonal braces connecting said legs, cross bars, and rectangular top frame, a table top mounted on said rectangular frame, and a receptacle for stationery hinged to one of the front legs and adapted to swing into and out of the cabinet through the open front of the skeleton metallic 115 frame. 120

2. A typewriter cabinet comprising a body, and a substantially rectangular receptacle open at one side and hinged at a corner thereof to the body of the cabinet to swing 125 130

into and out of the cabinet, the open side of the receptacle being closed by a wall of the cabinet when the receptacle is swung into the cabinet.

- 5 3. A cabinet comprising a metallic frame, side and top panels detachably secured thereto, and a receptacle open at one side and hinged at one corner to the metallic frame to swing into and out of the cabinet, 10 the said open side of the receptacle being closed by one of said panels when the receptacle is swung into the cabinet.

4. A cabinet comprising a body portion open at the front and bottom and closed at 15 the sides and top; and a receptacle open at one side and closed at the remaining sides and at the top and bottom, said receptacle being hinged at one corner to the body portion of the cabinet to swing into and out of 20 the same, the open side of the receptacle being outermost and accessible when the receptacle is swung out and being closed by a side wall of the body of the cabinet when the receptacle is swung into the cabinet.

25 5. A cabinet comprising a body portion open at the front and closed at the sides and top; and a substantially rectangular receptacle hinged on a vertical axis at one corner to a side of the cabinet at the front thereof 30 and adapted to swing into and out of the body of the cabinet through the open front thereof, said receptacle being closed at the top and bottom and at three sides thereof and open on the fourth side, the open side of 35 the receptacle being closed by the side wall of the cabinet to which the receptacle is hinged when said receptacle is swung into the cabinet.

6. A cabinet comprising a body portion; 40 and a receptacle hinged at one corner to swing into and out of the body portion of the cabinet, said receptacle comprising two rectangular metallic frames, a bottom panel secured to one frame, a top panel secured to

the other frame, and side panels uniting said frames.

7. A cabinet comprising a body portion; and a receptacle hinged thereto for movement into and out of said body portion, said receptacle comprising two metallic frames 50 each of which is hinged to the body of the cabinet, a top panel detachably connected to one of said frames, a bottom panel detachably connected to the other of said frames, and side panels which unite the frames and 55 are detachably connected thereto.

8. A cabinet comprising a metallic body frame, top and side panels detachably connected thereto; and two receptacles hinged to the body frame to swing into and out of 60 the same, each receptacle comprising two rectangular frames each carrying a hinged member by which the receptacle is hinged to the body frame, a top panel detachably secured to one of said rectangular frames, a 65 bottom panel detachably secured to the other rectangular frame, and side panels which unite said rectangular frames.

9. A cabinet comprising a body portion closed at the top and sides and open at the 70 back front and bottom, said body portion being formed of a skeleton metallic supporting frame with panels detachably secured thereto, and a receptacle hinged at one corner to the metallic frame to swing into and 75 out of the same, the only opening in said receptacle being closed by a wall of the body of the cabinet when the receptacle is swung into the cabinet.

Signed in the borough of Manhattan, city 80 of New York, in the county of New York and State of New York this 19th day of September, A. D. 1916.
